UNITED STATES PATENT OFFICE.

FRANZ A. FULLER, OF NEWARK, NEW JERSEY, ASSIGNOR TO THE J. E. MERGOTT COMPANY, OF NEWARK, NEW JERSEY, A CORPORATION OF NEW JERSEY.

DESIGN FOR A PAPER-CLIP AND PIN CUSHION.

50,062.

Specification for Design.

Patented Dec. 19, 1916.

Application filed October 21, 1916. Serial No. 127,022. Term of patent 3½ years.

To all whom it may concern:

Be it known that I, FRANZ A. FULLER, a citizen of the United States, residing in the city of Newark, in the county of Essex and State of New Jersey, have invented a new, original, and ornamental Design for a Paper-Clip and Pin Cushion, of which the following is a specification, reference being had to the accompanying drawings, forming a part thereof.

In the drawings, Figure 1 represents a plan view of a paper clip and pin cushion illustrating my new design. Fig. 2 represents a side elevation of the same; and Fig. 3 represents an under plan view of the same.

I claim:

The ornamental design for a paper clip and pin cushion, as shown.

FRANZ A. FULLER.

Witnesses:

FRED'K C. FISCHER,
W. H. CONKLIN.
